ABSTRACT OF THE DISCLOSURE

The invention is an infrared radiator for use in photometric analysis by selective absorption made up of a metal block provided with a reflective cavity in the shape of a paraboloid. In the block, a three stage bore, coaxial with the cavity, communicates therewith, the inner and smallest zone of the bore having disposed therein a lead bushing, while the next largest zone contains bent leads and the largest and exterior zone is filled by a closure. A narrow ledge flange prevents entry of the bushing into the cavity.

Gas analyzing instruments for determining the concentration of a gaseous component by the degree of absorption of infrared light passing through the sample or comparison gas require a source of infrared radiation. For this purpose electrically heated helical coils of wire are often used as emitters and the radiation is focused to form a beam by means of reflectors. In a suitable manner during the development of such infrared radiators, the emitter, the reflector and a window passing the infrared rays were combined into a complete assembly generally known as a radiator assembly.

A gas analyzing instrument as a whole is ordinarily used under normal atmospheric conditions, so it is generally not necessary that the radiator assembly be built completely gas-tight. Under special localities of use however, traces of the gases to be determined may be present in the surrounding atmosphere and find their way into the radiator assembly to cause seriously false indications by the instrument. It was found, for example, that in explosion-proof plants where rooms containing such instruments had been flushed with nitrogen the instruments gave false readings and that the cause of the error was due to traces of carbon dioxide in the flush or blanket gas.

It is therefore fundamentally advantageous to make the radiator assembly gas-tight. Since the individual parts of the assembly joined together by solder or cement can have greatly different coefficients of expansion it is necessary to bear in mind that material stresses developed as a result of heating action of the emitters must be avoided as much as possible lest gas-tightness be easily lost. It is therefore necessary, by temperature regulating measures, to avoid too great temperature contrasts in the various parts of the assembly.

The above safeguards and measures are incorporated in an embodiment of the invention which is easily, simply and economically constructed as a gas-tight radiator assembly. The assembly comprises a reflector block provided with a three-stage bore, axially symmetrical with the reflector, producing a zone of maximum diameter at the outer face of the block. A glass lead mount having heating current leads passing therethrough and fused therewith to form a vacuum tight juncture is secured gas-tight in said zone by solder or cement. A ceramic bushing having two small bores receiving two heater current leads

2

therethrough is disposed in the bore in the zone of smallest diameter.

The drawing shows the gas-tight beam emitting or radiator assembly in cross section.

The assembly comprises a reflector block 1 of metal having in its lower part 1a an outwardly open cavity 10 generally of the shape of a paraboloid, the wall of the cavity is of reflective material as shown at 2. The cavity being closed at its outer part by a window-pane 3 of material such as sodium chloride which is substantially transparent to infrared rays.

The upper portion 1b of the block is provided with a three-stage bore 4 so as to provide zones of greatest, intermediate and smallest diameter 4a, 4b, and 4c successively from the top of the block to the cavity 10, all being coaxial with the cavity or reflector. In the zone of greatest diameter there is disposed a disc-like glass member 5 as a wall entrance resting on the annular ledge 5' between bore zones 4a and 4b, the glass member 5 having passing therethrough vacuum-tight heating current leads 6 welded to the glass member in known manner. The mounting of the glass member in the bore is gas-tight as obtained in known manner such as by soldering or cementing. As shown in the drawing, the member 5 has a ring 5a cemented thereon, and the latter is soldered on the block 1.

A ceramic bushing 7 of relatively high thermal conductivity is disposed in the smallest zone 4c of the bore and rests with an end 7a on an internally projecting tapered annular flange 8 enclosing part of the cavity for the reflector.

The ceramic bushing is held in position substantially against the flange by means of the leads 6, which pass through two adjacent longitudinal bores 9 in the bushing, the leads being curved with respect to each other to provide shoulders as at 13 adjacent the opposite bushing end 7b and so providing greater distance between the leads in the glass member 5. In the cavity or reflector space 10 a helical coil emitter 11 is connected to the current leads as by welding.

A function of the ceramic bushing is to block off radiation from the glass member 5 and to protect it from excessive heat. Additionally, the heat flow in the leads is diverted by the bushing to parts of the metal reflector block especially at zone 4c. Hence the solder or cement joints for the glass member 5 are largely relieved from any thermal effects. The dissipated heat distributes itself quite uniformly to the massive metallic reflector block whereby objectionable temperature contrasts are avoided in the radiator assembly and the strain on the solder and cement is only as slight as possible. There is therefore an inherent uniform symmetrical temperature distribution in the radiator assembly and additionally a structure substantially geometrically symmetrical, with good mechanical stability of the radiation source. The latter is obtained by having the curved ends 12 of the helix so welded onto the leads 6 as to make the axis of the helix coaxial with that of the cavity 10.

If more radiation sources are necessary in an infrared gas analyzer they can be mounted in a common reflector block which provides a reflector for each source, so that separate sources can each be located in gas-tight assemblies.

The space within the bore and cavity may be vacuous so as to prevent any transfer of heat from the emitter and leads to the glass member 5, block 1 and window pane 3 by conduction or convection of gas. However the assembly may be filled with a substantially non-absorbing and chemically inert gas such as argon to a pressure of desired degree so as to reduce stress on the window pane 3.

In the latter case especially the clearances between the electrical leads and the bushing, and between the bushing and the block, should be as small as possible, without binding when the leads undergo change of temperature due to use and non-use of the instrument. While small clearances tend to produce a stagnant gas film between the bushing and the leads and block, which film is not highly conductive, convection currents to the glass member 5 are greatly reduced if not eliminated. The closeness of the clearances makes for better heat transfer by conduction from bushing to block. Also heat transfer ultimately to the cool block by radiation appears to account for much of the over-all heat transfer.

Since there is a temperature difference along part of the length of the bushing due to cooling by radiation to the block, the gas film is more stragnant or viscous at the cooler end of the bushing (upper end as shown in the drawing) and there is substantially termination of the film at the flange 8. The construction thus enables a degree of convection between the bushing and block near the mid portion of the length of the bushing. The same holds true to some extent between the leads of the bushing but fineness of the bores 9 precludes movement of any appreciable quantity of gas.

The invention claimed is:

1. A gas-tight radiator assembly for infrared gas analyzing instruments and having an electrically heated emitter in the form of a coil substantially at the focus of a reflector for directing a beam through a window-pane substantially transparent to infrared light and held by the improvement by solder on a reflector block characterized by the reflector block being provided with three-step outwardly open bore with its greatest diameter away from the apex of the reflector and axially symmetrical therewith, a glass entrance member cemented or soldered in said bore at the greatest diameter thereof, two electrical leads passing through the glass entrance member and fused vacuum-tight therein, and a ceramic bushing in the bore at the smallest diameter, said bushing have fine bores adjacent each other for passing said leads through the bushing.

2. A gas-tight radiator assembly as claimed in claim 1, wherein the ceramic bushing is disposed against an annular projection in the inner bore at the end of the bore toward the reflector.

3. A gas-tight radiation assembly as claimed in claim 1, wherein the mutual distance between the leads increases from a distance as small as possible where the leads are in the bores in the ceramic bushing to their greatest distance in the glass member.

4. A gas-tight radiation assembly as claimed in claim 1 wherein the ceramic bushing is composed of material having especially good heat conductivity.

5. A gas-tight radiation assembly as claimed in claim 1, said coil being in the shape of a helix coaxial with the three-step bore and the two outermost turns of the coil being welded onto the respective leads.

6. For an infrared radiation gas analyzer, a gas-tight radiator assembly comprising a reflector block of metal provided with a generally parabolic reflector cavity having a window pane substantially transparent to infrared radiation gas-tight on the block and over the cavity, the block being provided with a three-stage bore having three respective zones of reduced, intermediate, and maximum diameter successively in the order given from the cavity and coaxial therewith and open to the cavity, a ceramic bushing provided with lead bores therethrough and disposed in said portion of reduced diameter, leads in the bores in the bushing and extending in one direction 10 into the cavity and in the opposite direction to the exterior of the block, a glass entrance member symmetrical about the axis of the three-stage bore and secured gas-tight in said zone of maximum diameter, said leads passing gas-tight through said glass member.

25. 7. An assembly as claimed in claim 6, said block being provided with an annular flange between the bore at its zone of reduced diameter and the cavity for holding the bushing against movement into the cavity.

8. An assembly as claimed in claim 7, said leads being 30 bent apart in the zone of intermediate diameter to provide shoulder like bends to engage on the bushing to limit movement of the bushing on the leads and away from the flange.

9. An assembly as claimed in claim 7, said flange being 35 tapered toward the axis of the reflector cavity and contiguous therewith.

10. An assembly as claimed in claim 6, said bushing being closely adjacent to the leads and block at the zone of reduced diameter of the bore to mask the glass entrance 40 member from radiation within the cavity.
